ENGINE STARTER

John W. Fitz Gerald, Milwaukee, Wis., assignor to
 Briggs & Stratton Corporation, Milwaukee,
 Wis., a corporation of Delaware

Application August 1, 1941, Serial No. 405,016

2 Claims.

(Cl. 74—7)

This invention relates to engine starters of the type wherein the pinion is automatically propelled into mesh with the ring gear of the engine and automatically retracted upon starting of the engine.

In engine starters of this type it has always been necessary to provide some means of preventing the pinion from drifting or creeping forwardly into engagement with the ring gear while the engine is running. It is also necessary, especially with high-speed engines, to provide some means of preventing rebound of the pinion during its retraction.

Various expedients have been employed in the past for guarding against these two objectionable occurrences, but heretofore there has been no means by which both were eliminated with the same mechanism. It is, therefore, an object of this invention to provide an engine starter having a brake mechanism which applies a light force to hold the pinion against drifting or creeping forwardly and exerts a stronger force to prevent rebound during retraction of the pinion.

Another object of this invention is the provision of a brake mechanism so designed that the centrifugal force which obtains during revolution of the pinion as it is being retracted applies a braking force proportional to the speed of rotation of the pinion.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates one complete example of the physical embodiment of the invention constructed in accordance with the best mode so far devised for the practical application of the principles thereof, and in which:

Figure 1 is a view in side elevation of an engine starter embodying this invention, part of the pinion sleeve being broken away;

Figure 2 is a cross sectional view taken through Figure 1 on the plane of the line 2—2 and showing the manner in which the brake mechanism serves as an anti-creep detent;

Figure 3 is a view similar to Figure 2 but showing the brake mechanism in its position it occupies during retraction of the pinion; and

Figure 4 is a perspective view of the starter

mechanism forwardly of the plane on which Figures 2 and 3 are taken.

Referring now particularly to the accompanying drawing, in which like numerals indicate like parts, the numeral 5 designates the shaft of a starter motor upon which the starter mechanism indicated generally by the numeral 6 is mounted. The starter mechanism includes a pinion 7 arranged to move from a retracted position shown in Figure 1 into mesh with an engine ring gear 8.

The details of the starter mechanism as to the manner in which it is mounted on the shaft and the manner in which torsional and endwise resiliency are obtained from no part of this invention and thus have not been shown. For these features reference may be had to patent No. Re. 20,686, issued to John W. Fitz Gerald April 5, 1938.

Longitudinal translation of the pinion to and from operative driving position in mesh with the ring gear results from relative rotation between the pinion and an actuating member 9. The actuating member is driven from the starter shaft through a torsionally and endwise resiliency driving connection (not shown) and is externally threaded to receive an internally threaded sleeve 10 on the pinion.

Near its base or rear end, the threads of the actuating member 9 are cut down to form a groove 11. This groove coacts with a brake member 12 to provide an anti-drift or anti-creep detent which serves to hold the pinion against drifting forwardly into mesh with the ring gear while the engine is running.

The brake member 12 is a lever medially pivoted as at 13 to an annular flange 14 carried by the pinion sleeve. One end 15 of the lever is lighter than its other end 16. The light end 15 passes through an opening 17 in the wall of the sleeve 10 to engage the threads of the actuating member and enter the groove 11 when the pinion is fully retracted.

A light spring 18 confined between the heavy end 16 of the lever and the bottom of a socket 19 in the adjacent portion of the sleeve wall yieldingly imparts a turning moment on the lever member in a direction to engage its end 15 with the actuating member; but it is to be observed that the braking force applied by means of this spring is no greater than that heretofore in use in engine starters for the purpose of preventing the pinion from drifting or creeping forwardly.

During forward translation of the pinion when

it is being advanced into mesh with the ring gear the inertia of the pinion theoretically holds the pinion against rotation while the actuating member revolves within it. In actual practice, the pinion may revolve slightly but for all intents and purposes the pinion does not turn during its forward propulsion. Hence, the force acting on the brake mechanism is only that of the light spring 18.

However, at the time the engine starts, the pinion is revolving at a speed in excess of that of the actuator, and as a consequence retrograde translation of the pinion to its retracted position shown in Figure 1 takes place.

The differential in speed of rotation between the pinion and actuating member is so great especially with high speed engines that unless some means were provided to hold the pinion in its retracted position it would strike the base of the actuating member and bounce back toward the ring gear. In the past efforts were made to prevent this objectionable condition by means which would grip the pinion or its sleeve the instant retraction was completed. In other words, these past expedients did not prevent rebound. They merely limited it.

The present invention actually eliminates or prevents rebound by retarding the speed of rotation of the pinion during its retraction. This is accomplished by the simple expedient of so proportioning the weight of the lever that centrifugal force acting thereon rocks the lever in the direction to press its end 15 against the threads of the actuating member. Hence, the faster the pinion revolves, the greater will be the braking action.

From the foregoing description taken in connection with the accompanying drawing, it will be readily apparent that this invention provides an exceedingly simple manner of preventing rebound in automatic engine starters and of combining this function with that of an effective anti-drift or anti-creep device.

What I claim as my invention is:

1. In an engine starter having a power driven

member and a pinion adapted to be moved axially of said power driven member from and to a retracted position upon relative rotation between said parts: a screw threaded connection between the pinion and the power driven member for producing axial movement of the pinion from and to its retracted position upon relative rotation between said parts; and braking means revoluble with the pinion and having a portion acting on the power driven member to exert braking pressure thereon within the length of its threaded connection with the pinion to prevent creeping of the pinion out of its retracted position, said braking means having a centrifugally responsive part integral with said portion operable to increase the braking action of said portion upon the power driven member by an amount proportionate to the speed of rotation of the pinion.

2. In an engine starter having a pinion provided with an internally threaded sleeve, and an externally threaded actuating member on which the pinion sleeve is threaded so that relative rotation between said parts effects longitudinal translation of the pinion from retracted position to operative position and vice versa depending upon the direction of relative rotation; an outward flange intermediate the ends of the internally threaded sleeve; a medially pivoted lever mounted on the flange, one end of the lever being engageable with the thread of the actuating member through a hole in the wall of the sleeve to retard translation of the pinion, and the opposite end of the lever being heavier so that centrifugal force incidental to rotation of the pinion acts thereon to press the first-named end of the lever against the actuating member; and a light spring acting on the pivoted lever in a direction to engage said first-named end of the lever with the threads of the actuating member so as to at all times maintain a light braking action sufficient merely to hold the pinion against drifting.

JOHN W. FITZ GERALD.
